**OVERFLOW AND WASTE STOP CONTROL UNIT
FOR BATH TUBS OR THE LIKE**

Merritt J. Nelson, Grand Rapids, Mich., assignor to
Grand Rapids Plating Company, Inc., Grand Rapids,
Mich., a corporation of Michigan

Filed June 22, 1960, Ser. No. 61,066

Term of patent 14 years

(Cl. D91—3)

FIG. 1

FIG. 5

FIG. 2

FIG. 3

FIG. 4

Fig. 1 is a front elevational view of the overflow and waste stop control unit for bath tubs or the like embodying my new design;

Fig. 2 is a side elevational view thereof;

Fig. 3 is a bottom plan view thereof;

Fig. 4 is a top plan view thereof; and

Fig. 5 is a reduced fragmentary perspective view thereof with the handle member omitted for convenience of illustration.

I claim:

The ornamental design for an overflow and waste stop control unit for bath tubs or the like, substantially as shown.
